UNITED STATES PATENT OFFICE.

ARCHIE A. KINION, OF SAND SPRINGS, OKLAHOMA.

COLLAR-HOLDER.

1,242,451.

Specification of Letters Patent.

Patented Oct. 9, 1917.

Original application filed September 18, 1916, Serial No. 120,745. Divided and this application filed January 25, 1917. Serial No. 144,475.

To all whom it may concern:

Be it known that I, ARCHIE A. KINION, a citizen of the United States, residing at Sand Springs, in the county of Tulsa and 5 State of Oklahoma, have invented certain new and useful Improvements in Collar-Holders, of which the following is a specification.

The present application is a division of 10 the application filed September 18, 1916, Serial No. 120,745.

This invention relates to improvements in collar and necktie holders, and has for one of its objects to provide a simply constructed device whereby the collar may be 15 connected to the neck band of a shirt without employing a collar button.

Another object of the invention is to provide a device whereby the collar may be 20 secured to the neck band of a shirt without structural change in the collar or the neck band.

Another object of the invention is to provide 25 a device of this character which will support the collar upon the shirt band and at the same time support a neck tie in position at the back of the neck.

With these and other objects in view, the 30 invention consists in certain novel features of construction, as hereinafter shown and described and then specifically pointed out in the claims; and in the drawings illustrative of the preferred embodiment of the invention—

35 Figure 1 is a perspective view of a collar equipped with one of the improved holders.

Fig. 2 is an enlarged transverse section on the line 2—2 of Fig. 1.

Fig. 3 is an enlarged detached perspective view of the improved device.

Fig. 4 is a view of the blank from which the improved device is constructed.

Corresponding and like parts are referred 45 to in the following description and indicated in all the views of the drawings by the same reference characters.

The improved device is formed from a strip of material, preferably of celluloid or like material or compound, or of metal suitably plated or otherwise ornamented or protected. The device is formed initially of a strip of material represented as a whole at 50 in Fig. 4, rounded at the ends and with a U shaped cleft cut through the body where- 55 by a relatively elongated tongue, repre-

sented as a whole at 11, is produced. The tongue portion of the device is first bent at its root, indicated by the dotted line 12, substantially into parallel relation to the lower part of the body 10 to produce the 60 portion 13, and thence bent into an open hook shaped portion 14 which likewise extends for the major portion of its length in parallel relation to the portion 13. Near its free end the hook shaped portion 14 is 65 bent inwardly toward the body 10, as indicated at 15. At its lower end the body portion 10 is bent into parallel relation to the major part of the body to produce a hook like portion 16, the portion 16 being 70 disposed at the opposite side of the body from the portions 13—14. At its upper end the body is bent over into hook like shape, as shown at 17, the confronting terminals of the portions 16—17 being spaced 75 apart for a considerable distance, as shown.

The completed device is clearly shown in Fig. 3.

The improved device is applied by inserting the portion 14 through the button 80 hole at the rear of the collar, indicated at 18, and moved therein to bring the material of the collar which is located below the button hole into the space between the portion 13 and the body 10 of the device. This 85 leaves the major part of the body and the hook shaped portions 16—17 externally of the outer ply of the collar, or between the folds when applied to a turn-over collar.

A portion of the neck band of the shirt 90 is represented at 19 with the outer flap 20 secured at its upper edge to the upper edge of the neck band, and the collar having the attachment thereon is disposed in position around the neck and the portion 14—15 95 of the tongue forced upwardly between the neck band and the flap. The depressed terminal 15 compresses the flap against the adjacent portion of the collar, and thereby materially increases the friction between 100 the parts. It will be noted by reference to Fig. 2 that the depressed portion 15 of the device deflects the flap and presses it against the adjacent portion of the collar, thereby effectually preventing the accidental 105 displacement of the device. The pressure exerted by the resiliency of the member 14—15 against the adjacent portions of the flap and the collar will be sufficient to prevent the collar and attachment from moving 110

downwardly, while the bend at the juncture of the portions 13—14 operates to prevent the upward movement of the collar. The portions 16—17 coact to support a neck tie, indicated at 22, and prevent its displacement. The neck tie may be placed in position before the collar is disposed around the neck of the wearer, or after the collar is disposed in position, as may be preferred.

10 The improved device is simple in construction, can be inexpensively manufactured, and by means of which the collar may be easily and quickly attached to the shirt without the necessity for employing the 15 usual collar buttons.

The device thus serves not only as a support for the collar but as a guide and support for the neck tie.

Having thus described the invention, what 20 is claimed as new is—

1. A collar holder including a body bent at its extremities to provide confronting hooks defining a tie receiving loop with the inlet thereto between the bills of the hooks 25 and having a tongue struck from the body and bent upon itself to provide a hook for

connecting the holder with a collar, the tongue terminating in an upstanding wing converging at its free extremity toward the body and adapted for engagement with the 30 neck band of a shirt for connecting the collar thereto.

2. A collar holder formed from a single piece of resilient material and including a body bent at its extremities to produce 35 confronting hooks and forming a tie receiving loop, the inlet to the loop being between the bills of the hooks, said body having a tongue struck longitudinally therefrom and bent upon itself to provide a hook disposed for engagement with a collar for connecting the holder thereto, the free extremity of said hook terminating in an upstanding wing disposed for engagement 40 with a shirt band and provided adjacent its upper extremity with a depression for clamping the band between the wing and the body to prevent displacement of the collar.

In testimony whereof I affix my signature. 45

ARCHIE A. KINION. [L.S.]
